UNITED STATES PATENT OFFICE.

GEORGE F. ZWILLING AND CHARLES W. RICHARDS, OF CLEVELAND, OHIO,
ASSIGNORS TO ACME MACHINERY COMPANY, OF CLEVELAND, OHIO.

NUT-HOLDER.

SPECIFICATION forming part of Letters Patent No. 770,144, dated September 13, 1904.

Application filed January 5, 1904. Serial No. 187,845. (No model.)

To all whom it may concern:

Be it known that we, GEORGE F. ZWILLING and CHARLES W. RICHARDS, citizens of the United States, and both residents of Cleveland, in the county of Cuyahoga and State of Ohio, have invented a new and Improved Nut-Holder, of which the following is a full, clear, and exact description.

This invention relates to a nut-holder designed especially for automatic nut-tapping machines.

The object of the invention is to provide means for holding the nut with that firmness necessary to the operation of the tap therein and yet allowing the nut a certain bodily movement transversely of the tap, so that should the nut not be true it may be shifted laterally as the tap enters the nut and the tap allowed to operate evenly notwithstanding that the sides of the nut may not be true. In attaining this end we provide a stand mounted on the table of the machine under the nut-feeding chute and having a nut-holder proper arranged to slide horizontally therein laterally of the tap. In this nut-holder the nuts are held free to move vertically, and therefore it will be seen that by these combined movements the nut may be shifted sidewise or upward, so that the orifice in the nut will correspond precisely to the true position of the tap.

This specification is an exact description of one example of our invention, while the claims define the actual scope thereof.

Reference is to be had to the accompanying drawings, forming a part of this specification, in which similar characters of reference indicate corresponding parts in all the views.

Figure 1 is a front elevation of the nut-holder with parts in section. Fig. 2 is a horizontal section on the line 2 2 of Fig. 1, and Fig. 3 is a vertical longitudinal section on the line 3 3 of Fig. 1.

10 indicates the bed or table of the nut-tapping machine, and the dotted lines 11 may be taken to represent the nut-feeding chute thereof. Suitably mounted on the table 10 is the stand 12 of the nut-holder, said stand having a vertical passage 12^a formed therein, and a

horizontal passage 12^b, both of said passages 50 crossing each other and opening at the inner or rear side of the stand and the vertical passage 12^a running through to the front of the stand at the lower portion, as shown in Figs. 1 and 3, thus allowing the proper operation 55 of the nut-ejector 14. So far as this invention is concerned this ejector 14 may be of any form desired. We have illustrated in the drawings, however, an ejector similar to that disclosed in our application for nut-tapping 60 machines, filed June 12, 1903, Serial No. 161,181.

The nut-holder proper comprises a horizontally-extending block 15, which fits snugly in the horizontal passage 12^b of the stand, so as 65 to move horizontally therein. Secured to the rear side of the block 15 are two pins 16, against which respectively bear springs 17, these springs serving to hold the block 15 70 yieldingly in its central or intermediate position. Said springs should be suitably supported on the stand. As here shown, they are attached to cleats or plates 18, which are bolted to the rear sides of the stand and extend across the horizontal opening 12^b to hold 75 the block 15 properly in place.

The front wall of the vertical passage 12^a of the stand has fastened thereto a liner 19, held in place, for example, by bolts 20, extending through the front of the stand. The 80 block 15 has a vertical passage 15^a formed therein, this passage opening at the front side of the block and having liners 21 and 22 secured therein, the liners 21 being held by bolts 23 and the liner 22 by bolts 24. The 85 said liners 19, 21, and 22 extend above and below the block 15, as shown in Figs. 1 and 3, and they form a vertical chute, in which the nuts lie superimposed, as indicated by the broken lines in Fig. 3 and as is fully set forth in 90 the copending application above referred to.

The dotted lines 25 in Fig. 3 indicate the tap and show its position with respect to the nut-holder. The block 15 has a relatively large opening 15^b formed in its rear side, this opening communicating with the before-mentioned vertically-extending opening 15^a, and the liner 22 has an opening 22^a therein cor-

2
responding with the opening 15^b. The front wall of the stand 12 has an opening 12^c therein and the liner 19 an opening 19^a, both in line with the opening 15^b and the tap. The 5 nut being tapped is dropped through the space between the liners 19, 21, and 22, and is held by the coaction of the ejector 14 and the lowermost nut in position to be engaged by the tap. As the tapered tap passes through 10 the openings 15^b and 22^a and engages the hole in the nut should the nut be out of square or otherwise not true the block 15 will give to one side or the other, thus compensating by 15 a lateral movement for the inaccuracy in the nut, and the nuts will be free to move upward in the chute, and in this manner the compensating movements of the nut will be complete. In this connection it should be remembered that the springs 17 are set to hold the 20 block 15 normally in central or true position.

Various changes in the form, proportions, and minor details of our invention may be resorted to at will without departing from the spirit and scope thereof. Hence we consider 25 ourselves entitled to all such variations as may lie within the intent of our claims.

Having thus described our invention, we claim as new and desire to secure by Letters Patent—

- 30 1. In a nut-holder, the combination of a stand, and a nut-holder proper arranged to slide therein, the nut-holder proper having a nut-chute extending transversely of the line of sliding movement.
- 35 2. In a nut-holder, the combination of a stand, a nut-holder proper arranged to slide therein, the nut-holder proper having a nut-chute extending transversely of the line of sliding movement, and a spring for yieldingly 40 holding the nut-holder in true position.
- 40 3. A nut-holder, comprising a stand having a horizontal and a vertical passage, said passages crossing each other, a nut-holder proper arranged to slide in the horizontal passage,

and walls carried by the nut-holder proper 45 and lying loosely in the vertical passage of the stand, said walls constituting a chute for the nuts.

4. A nut-holder, comprising a stand having a horizontal and a vertical passage, said passages crossing each other, a nut-holder proper 50 arranged to slide in the horizontal passage, walls carried by the nut-holder proper and lying loosely in the vertical passage of the stand, said walls constituting a chute for the 55 nuts, and a spring for yieldingly holding the nut-holder proper in true position.

5. A nut-holder, comprising a stand having vertical and horizontal passages therein, a block arranged to slide in the horizontal passage, and liners carried by the block and extending vertically to form a chute for the nuts. 60

6. A nut-holder, comprising a stand having vertical and horizontal passages therein, a block arranged to slide in the horizontal passage, 65 liners carried by the block and extending vertically to form a chute for the nuts, and a spring actuating the block to hold it yieldingly in normal position.

7. In a nut-holder, the combination of a 70 stand, and a holder proper movable therein, said holder having a chute extending transversely to the line of movement of the holder in the stand.

8. The combination of a nut-holder capable 75 of receiving and bodily carrying the nut, means for mounting the nut-holder so as to permit movement thereof in one plane, and yielding means for holding the nut-holder in position. 80

In testimony whereof we have signed our names to this specification in the presence of two subscribing witnesses.

GEORGE F. ZWILLING.
CHARLES W. RICHARDS.
